Attorneys

UNITED STATES PATENT OFFICE

HARRY W. NEAL, OF INDIANAPOLIS, INDIANA, ASSIGNOR TO HALL-NEAL FURNACE COMPANY, OF INDIANAPOLIS, INDIANA

FURNACE

Application filed October 21, 1929. Serial No. 401,074.

This invention relates to the art of heating furnaces of the warm air type and is directed particularly to a peculiar combination of conducting and radiating surfaces arranged about a source of heat to afford a greater transfer of heat therefrom to air passing thereover than has heretofore been obtained.

It is also an object of the invention to provide means supplying a maximum surface to be "wiped" over by a current of air to make available that heat normally radiated to the outer wall or housing of the furnace.

Other objects reside in the unique structure provided for the above purposes which may be produced at a relatively low cost of production and which is practically indestructible.

These and other minor objects are accomplished by the structure as illustrated in the accompanying drawings, in which—

Fig. 1 is a fragmentary front elevation of a furnace embodying the invention; and

Fig. 2, a horizontal section through the furnace on the line 2—2 in Fig. 1.

Like characters of reference indicate like parts throughout the several views in the drawings.

I form a furnace to have a central fire-box 10 with the usual outer housing 11 surrounding it at a distance therefrom. Within the space between the fire-box 10 and the housing or wall 11, I place radiating drums 12 and 13, each drum having a plurality of vertically disposed fins 14 projecting outwardly from its walls both toward the fire-box 10 and toward the wall 11. These fins 14 are preferably integral extensions from the drum walls although not necessarily so. The detailed construction of a drum having integral fins forms the subject matter of my co-pending application Serial No. 401,073, filed October 21, 1929.

On the inside of the wall 11, I place a radiating shield comprised of a plurality of vertically disposed sections 15 arranged consecutively one after another around the wall 11. For ease of construction and to secure rigidity, the wall 11 is itself built up from sections 16 bolted together at interlocking joints 17. Each wall section 16 is separately assembled

with its corresponding shield section 15 prior to the placing of the wall section 16 into the complete wall 11. In this prior assembly, the section 15 is secured to the section 16 by means of stove bolts 18.

Each shield section 15 has a plurality of V-depressions 19 formed vertically from the inner side, the reverse sides of such depressions contacting the wall 11 so as to space the section 15 at a distance inwardly from the wall 11 to leave an air space therebetween. The lateral vertical edges of section 15 are engaged under and within the folds of the wall section 16 at each of the joints 17.

Now between each of the depressions 19 the section 15 is bent sharply inwardly and thence back and around again to form the inwardly projecting fin 20 having a double thickness of metal by reason of such bending. The spacing of the fins 20 is such as to bring one between each of the fins 14 projecting from the drums 12 and 13, as indicated in Fig. 2.

As is customary, cold air is taken in at or near the bottom of the furnace to within the space between the fire-box 10 and the wall 11. This air is set in motion by the difference in temperature produced by the heated fire-box and drum surfaces. Heat from the drum will be conducted outwardly along the fins 14. Heat will also be radiated from the drums and be absorbed by the various sections 15 making up the shield around the wall 11.

This heat so absorbed will in turn be conducted in part inwardly along the fins 20.

I am aware that radiating fins have been heretofore employed around fire-boxes, but I believe it to be new to intercept and return heat radiated outwardly to the outer wall. By reason of the construction above described, air passing upwardly not only "wipes" off heat from the drum fins 14 but also at the same time "wipes" off heat from the fins 20. The outer wall 11 is maintained at a much lower temperature by reason of the shield therewithin and the air spaces between the shield and the wall.

I claim:

1. In a furnace, a heated sheet metal casing, vertical fins of folded sheet metal dis-

posed about said casing, a sheet metal housing surrounding said surface, and similarly folded fins projecting from said housing toward said casing, each of said housing fins being disposed between two adjacent casing fins.

2. In a furnace, a heated casing, a housing around said casing, a hollow shield spaced between said casing and said housing, vertically disposed fins projecting from one side of the shield toward the casing and from the other side toward the housing, and vertical fins disposed about said housing and projecting to between the fins on said shield, the edges of the last said shield fins and of the housing fins terminating before contacting the respective housing and shield.

In testimony whereof I affix my signature.

HARRY W. NEAL.
